UNITED STATES PATENT OFFICE.

HENRY A. FINK, OF SYRACUSE, NEW YORK, ASSIGNOR TO CONTINENTAL CAN COMPANY, INC., OF SYRACUSE, NEW YORK, A CORPORATION OF NEW YORK.

SEALED METAL CONTAINER.

Application filed August 16, 1923. Serial No. 657,726.

The invention relates to new and useful improvements in sealed metal containers, and more particularly to a metal container which may be readily opened by breaking the sealing means therefor.

An object of the invention is to provide a container of the above type wherein the flange on the end and the flange on the body portion of the container are substantially housed by an integral sealing ring, which sealing ring is provided with means at substantially diametrically opposite points whereby the same may be broken.

A further object of the invention is to provide a container of the above type wherein in the inner wall of the sealing ring is cut away so as to facilitate its removal after the same has been broken.

These and other objects will in part be obvious and will in part be hereinafter more fully disclosed.

In the drawings which show by way of illustration one embodiment of the invention—

Figure 1 is a view partly in side elevation and partly in section showing a container embodying the invention;

Fig. 2 is a plan view of the same;

Fig. 3 is an enlarged sectional view on the line 3—3 of Fig. 2;

Fig. 4 is an enlarged sectional view on the line 4—4 of Fig. 2, and

Fig. 5 is an enlarged sectional view on the line 5—5 of Fig. 2.

In the drawings I have shown my improved sealed container as consisting of a body portion 1 preferably made of metal. Said body portion has an outwardly projecting flange 2 which is formed by rolling the metal outwardly, downwardly and inwardly. The body portion is contracted as indicated at 3 so that the extreme outer edge of the flange 2 is substantially over the outer wall of the container body. The flange 2 as shown in the drawings, is rolled so as to form a hollow flange. The inner wall 4 of the mouth of the container body is substantially vertical.

The container is closed by means of an end 5 which has a central depression 6 which provides a vertical wall 7 which is adapted to frictionally engage the inner wall 4 at the mouth of the body portion. Said end is provided with an outwardly extending flange 8 which is rolled downwardly and inwardly

as shown in the drawings, and the outer edge of this flange is substantially in line with the outer edge of the flange 2, and directly above the same. In other words, the flange on the end overlies the flange on the body portion. 60 This flange on the end is also shown as hollow.

While I prefer to make these flanges hollow so as to give more resilience to the closing means, it will be understood, of course, that from certain aspects of the invention, the metal forming the flanges may be closed down into substantial contact. Between the flanges there is a sealing means 9 which may be of any suitable character. After the end has been seated in the mouth of the container body, the container is then sealed by means of a sealing ring 10. Said sealing ring 10 is provided with a portion 11 which overlies the flange of the end and also with a portion 12 which extends over into the depression in the end. Said portion 12 is substantially vertical, and in the preferred form of the invention, extends to the full depth of the depression where it is turned inwardly to 70 form a horizontal ledge 13.

Said sealing ring has a portion 14 which extends downwardly across the flanges. Said sealing ring is adapted to be turned at 15 underneath the flange on the body portion. The sealing ring is placed on the flanges before the part 15 is turned underneath the body flange. A chuck is placed inside of the ring resting on the horizontal ledge 13, which not only holds the ring, but causes the end to be well seated in the container body, after which the edge 15 is spun or turned in any suitable way underneath the flange 2, and this tightly binds the two flanges together. Inasmuch as the flanges are hollow, they will yield slightly to the pressure of the chuck, and thus it is that there is resiliency in the parts united, which enables them to be forced into very close contact and the resiliency of these parts tends to hold the seal tight. 100

As clearly shown in Fig. 2 of the drawings, I have provided a breaking means 16 for said sealing ring, and there are two breaking means at diametrically opposite points. The breaking means on opposite sides are similar in construction, and a description of one will answer for the other. This breaking means is in the form of an inwardly projecting tongue or member 110

which is integral with the wall 12 of the sealing ring. The tongue has an opening 17 therethrough for an implement to be used in manipulation of the breaking member to

5 rupture the metal of the sealing ring.

Said sealing ring is provided with starting cuts indicated at 18 and 19 which are substantially in line with the side edges of the breaking tongue or member. The metal 10 is cut through at these points for a short distance from the edge of the flange or ledge 13 toward the vertical wall 12, and preferably to the wall 12. In my prior application, Serial No. 657,725, filed of even date 15 herewith, I have shown a container closed by a sealing ring having a breaking member similar to that above described at one side only, and the present breaking member operates as more fully set forth in my prior 20 application. In the present invention, I have two breaking members diametrically opposed to each other, so that when the breaking members are turned to break the sealing ring, it will be separated into two 25 pieces.

It will be noted that this sealing ring substantially houses the flanges. That is, it extends across the top, down the sides, and underneath, and the inner and outer edges of 30 the sealing ring are only separated by a distance slightly greater than the thickness of the metal forming the flanges. The result is that the two flanges will be strongly housed and secured in sealed contact, one 35 with the other. Inasmuch as the can to which my improved sealing ring is applied is a circular can, it will readily be seen that with a sealing ring of the above character, if it is broken only in one place, it will be 40 extremely difficult to remove the ring, as it can neither be lifted up nor moved sidewise to disengage it from the flanges. It will have to be unfolded, which is rather difficult 45 to accomplish. By breaking the ring in two places, however, it can be much more readily unfolded sufficiently to remove it from the container.

As a further means to aid in removing the sealing ring, I have shown the ring as provided with cut away portions 20, 20. These 50 cut away portions are in the inner vertical portion of the sealing ring and extend from a point near the inwardly projecting ledge 13 to a point well up to the upper plane of 55 the flange on the cover. By this construction, the unfolding of the sealing ring can be very much more readily accomplished, as the amount of metal left in the inner vertical wall of the ring which is to be straightened out has been greatly reduced.

My improved sealed container is especially adapted for use in connection with goods which are to be put under vacuum, or pressure. It will be understood that the 60 end of the container having the sealing ring

is preferably applied by the manufacturer. The container is then packed, after which the other end of the container is put on by the packer.

When it is desired to open the package, 70 the sealing ring is broken and stripped from the container, after which the closing end can be readily removed, and thus the contents rendered accessible. The container may be readily reclosed by placing the end 75 back in the mouth of the container and the vertical wall on the end is of sufficient length to frictionally engage the wall at the mouth of the container, and thus hold the end on the container. It will readily be seen that 80 the container body with its rolled edge makes a very neat and attractive container for any use. Likewise, where the sealing ring is entirely separate and independent 85 from the closing end and container body, there are no objectionable raw edges of the metal left on the end or container body after the sealing ring is stripped therefrom.

While I have shown two breaking members oppositely disposed, it is understood 90 that a greater number may be used if found necessary. Furthermore, while I have shown and described the sealing ring as extending over into the depression of the end or closure for the container, and as having 95 a vertical wall with a horizontal ledge at the lower end thereof, it will be understood that from certain aspects of the invention, this structure may be changed, the essential feature being that the sealing ring shall extend 100 over the central portion of the container sufficiently to serve as a strong anchorage when the upper edge of the sealing ring is turned underneath the flange on the can body.

While I have described the ledge 13 as having starting cuts, it may be that these starting cuts will be only part way cut through the metal. It is desirable, however, to have a starting point for the rupture of 110 the metal, so that when the breaking tongue is raised as a lever, the ledge 13 between the breaking members being curved will serve to hold said ledge down against the upward 115 pry of the breaking members, and this will insure that the metal will start to rupture in alignment with the side edges of the breaking tongues.

It is obvious that the manner of breaking the sealing ring and the details of construction of the ring may be widely varied without departing from the spirit of the invention as set forth in the appended claims.

Having thus described the invention, what I claim as new and desire to secure by Letters-Patent, is—

1. A sealed metal container comprising a cylindrical body portion having an outwardly extending flange, an end having a central depression adapted to frictionally 120

engage the inner surface of the wall of the body portion of the mouth thereof, said end having an outwardly extending flange adapted to overlie the flange on the body portion, an integral sealing ring overlying the flange on the end and extending down into said depression in the end, said sealing ring at the outer edge thereof extending downwardly across the flanges and adapted 5 to be turned underneath the flange on the body portion for holding said flanges in tight engagement and sealing the container, a sealing means between the flanges, said sealing ring having an inwardly projecting 10 breaking member at the inner lower edge of the ring, the vertical wall of the sealing ring being provided with cut-away portions to aid in releasing the ring after it is torn across through the aid of the breaking member.

2. A sealed metal container comprising a body portion having an outwardly extend-

ing rolled flange, an end having a central depression adapted to frictionally engage the inner surface of the wall of the body portion at the mouth thereof, an outwardly extending rolled flange overlying the flange on the body portion, an integral sealing ring overlying the flange on the end and extending into said depression, said sealing ring at the outer edge thereof extending downwardly across the flanges and underneath the rolled flange on the body portion, a sealing means between the flanges, said sealing ring having an inwardly projecting 35 integral member at the inner lower edge of the ring, and a starting cut in line with one edge of the breaking member, the inner vertical wall of the sealing ring being provided with cut-away portions to aid in releasing 40 said sealing ring after it is broken.

In testimony whereof, I affix my signature.

HENRY A. FINK.
